Primary Examiner — Alison M Ofstun(74) *Attorney, Agent, or Firm* — Grogan, Tuccillo & Vanderleeden, LLP(57) **CLAIM**

The ornamental design for a hair straightening and styling appliance, as shown and described.

DESCRIPTION

FIG. 1 is a front perspective view of a hair straightening and styling appliance showing a new design;
 FIG. 2 is a rear perspective view thereof;
 FIG. 3 is a left side elevational view thereof;
 FIG. 4 is a right side elevational view thereof;
 FIG. 5 is a bottom plan view thereof;
 FIG. 6 is a top plan view thereof;
 FIG. 7 is a front elevational view thereof; and,
 FIG. 8 is a rear elevational view thereof.
 The broken lines in the figures illustrate portions of the article which form no part of the claimed design.
